Primary Examiner — Elizabeth J Oswecki

(74) Attorney, Agent, or Firm — Nath, Goldberg & Meyer;
Jerald L. Meyer; Scott C. Langford(57) CLAIM

The ornamental design for a sleigh cork cage ornament, as shown and described.

DESCRIPTION

FIG. 1 is a perspective view of a sleigh cork cage ornament showing my new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines shown in the drawings represent portions of the sleigh cork cage ornament that form no part of the claimed design.
